CONSTRUCTION OF MERCURY SWITCHES

Application filed July 31, 1931. Serial No. 554,185.

This invention relates to improvements in the construction of mercury tube switches and more particularly to that type in which a portion of the mercury is bodily raised by magnetic means to close and open the circuit through the switch.

Mercury tube switches including a sealed tube containing a quantity of mercury and having spaced apart electrodes seated in the walls of the tube requiring the tilting of the switch to cause the mercury to flow into and out of contact with the electrodes has a recognized place in the switch art. There are times when it is neither practicable nor desirous to tilt a switch to open or close an electric circuit therethrough and it is an object of this invention to provide a mercury tube switch with means for bodily moving a portion of the mercury therein to open and close the circuit therethrough while the switch tube is stationary.

With these and other objects in view, reference is made to the accompanying sheet of drawing which illustrates a preferred form 25 of this invention with the understanding that minor detail changes may be made without departing from the scope thereof.

In the drawing—

Figure 1 is a view partly in vertical central section and partly in side elevation of this 30 improved switch before the filling stem has been tipped off.

Figure 2 is a view in horizontal section, taken on the line 2—2, Figure 1, looking in 35 the direction of the arrows.

Figure 3 is an enlarged detail view in perspective of the operating parts removed from within the switch tube.

Figure 4 is a view similar to Figure 1 of a 40 completed switch in open position showing the positions of the interior and exterior operating means.

Figure 5 is a view similar to Figure 4, 45 illustrating the switch in closed position.

In the embodiment of this invention as 50 illustrated, the container or tube 1 is preferably a glass tube closed at one end with electrodes 2 and 3 welded upon leading in wires 2a and 3a, which wires with a filling stem 4 between them are sealed in the other end and a body of mercury 5 within the sealed tube. This switch is adapted to be firmly held with 55 the sealed end down, as shown. In order to bring the mercury into and out of contact

with both electrodes, the following construction is employed within the tube 1.

One electrode 2 is bent at right angles and is terminated in an eye 6 about the longitudinal axis of the tube 1 which acts as a guide for one end of a longitudinally movable rod or shaft 7, preferably of the same electrical conducting material as the electrodes 2 and 3. The other end of the rod 7 is affixed to the underside of a disc 8 of magnetic metal adapted to reciprocate within the tube 1, and provided with a small compression spring 9 on the side next to the closed end of the tube 1. Between the guiding eye 6 and the disc 8 a cup 10 is centrally mounted upon the rod or shaft 7 with its top opening in the direction of the disc 8. The other electrode 3 is conducted through a surrounding sleeve of glass 11, or other insulating material, to a point just above the uppermost travel of the cup 10 and is then bent over and back, so that when the cup 10 is at its lowermost point the end of the electrode 3 is spaced apart from the cup and at its uppermost point the end of the electrode is received within the cup.

A quantity of mercury 5 is contained within the tube 1 of sufficient amount, so that when the cup 10 is at its lowermost point, the cup will be submerged and the end of the electrode 3 will be spaced apart thereabove and out of contact. When the disc 8 and shaft 7 are reciprocated toward the closed end of the tube, the cup 10 filled with mercury will bodily move the contained mercury into contact with the free end of the electrode 3, closing the circuit from said electrode through the mercury in the cup 10, the shaft 7 and body of mercury 5 in the tube to electrode 2. As the cup 10 is submerged in the main body of the mercury at each reciprocation, the contents of the cup is renewed after each break of the circuit.

In the tilting mercury tube switch some external means is employed to impart the tilting movement to cause the mercury to flow into and out of contact with the two electrodes to close and open the circuit within the tube and likewise in this type where the tube does not tilt some external means must be employed to impart reciprocation to the rod or shaft 7 to carry the cup 10 full of mercury into and out of contact with the electrode 3. It has been heretofore said that the disc 8 is of magnetic metal and, in this instance, a magnet 12 is arranged exterior of the tube 1 which may be caused to approach

and depart, by any known or desired means, to and from the closed end of the tube 1 causing the magnetic disc 8 to be reciprocated. The tube 1 to be operated must be held with its sealed end lowermost. When the magnet 12 approaches the closed end of the tube 1 the disc 8 is attracted thereby causing the rod or shaft 7 to move through its lower guide 6 and bodily carry the mercury contained in the cup 10 into contact with the bent back end of the electrode 3 to complete the circuit. The spring 9 on the top of the disc 8 acts as a shock absorber to prevent the disc from breaking or cracking the closed end of the tube 1. When the magnet 12 is moved away from the tube to remove the magnetic field from the disc 8, the weight of the disc and associated parts causes the cup to descend and be submerged within the mercury 5 with the bottom of the rod or shaft 7 resting upon the sealed end of the tube.

Switches of this type are made in a machine in which leading in wires carrying the electrodes and a filling stem are held and positioned in a work holder, the open end of a tube closed at the other end inserted thereon, the walls heated to plasticity and pressed together to embrace and seal the electrodes and filling stem, as shown in Figure 1. In sealing the electrodes in the glass bulb it is necessary that the wire has the same coefficient of expansion as the glass and it is common practice to weld a piece of such material to the electrodes as shown in the drawing as 2a and 3a which serve as lead in wires. As shown, the bottom of the rod or shaft 7 is expanded to form an enlarged base which rests upon the open end of the filling stem 4 so that when the parts 2, 6, 7 and 8 are assembled the electrode 2 may be placed in the work holder and position the parts during the sealing of the open end of the tube. The tube is reversed after sealing for the removal of the contained air and insertion of the mercury and inert gas through the filling stem 4, whereupon the parts 7 and 8 move away from the open end of the filling stem. After the insertion of the mercury and gas the filling stem 4 is tipped off as shown in Figures 4 and 5.

What I claim is:

1. A fluid switch including a sealed container, a body of electric conducting fluid therein, electrodes passing through the walls thereof, one entering and normally submerged in the conducting fluid and the other spaced apart therefrom, and means adapted to be reciprocated within the container while in contact with the conducting fluid to bodily transport a portion of the conducting fluid upon the reciprocating means from the main body to contact the separated electrode to close the circuit, said means including a rod conductor always in contact with the said fluid and having a disc of magnetic material

carried thereon adapted to be reciprocated by an external magnet.

2. A fluid switch including a sealed container, a body of electric conducting fluid therein, electrodes passing through the walls thereof, one entering and normally submerged in the conducting fluid and the other spaced apart therefrom, and means adapted to be reciprocated within the container while in contact with the conducting fluid to bodily transport a portion of the conducting fluid from the main body to contact the separated electrode to close the circuit, said means including a rod conductor always in contact with the said fluid and having a disc of magnetic material carried at one end thereon adapted to be reciprocated by an external magnet. 70

3. A fluid switch including a sealed container, a body of electric conducting fluid therein, electrodes passing through the walls thereof, one entering and normally submerged in the conducting fluid and the other spaced apart therefrom, and means adapted to be reciprocated within the container while in contact with the conducting fluid to bodily transport a portion of the conducting fluid from the main body to contact the separated electrode to close the circuit, said means including a rod conductor always in contact with the said fluid and having a disc of magnetic material carried at one end thereon adapted to be reciprocated by an external magnet, and a cup upon the rod normally submerged in the fluid at one end of its reciprocation adapted to bodily transport in the cup a portion of the fluid to contact the separated electrode at the other end of its reciprocation. 80

4. A fluid switch including a sealed tubular container, a body of electric conducting fluid therein, electrodes passing through the walls thereof, one of which is normally submerged at all times in the said fluid and is terminated in an eye about the longest axis of the container and the other normally spaced apart and out of contact with the fluid, a reciprocable conducting rod passing through the eye of the submerged electrode terminating in a disc of magnetic material at the other end normally spaced apart from the end of the container, and a cup surrounding and attached to said rod between the electrode eye and the disc normally submerged in the fluid, said disc adapted to be moved toward the adjacent end of the container by an external magnet to carry the cup to submerge the separated electrode in its contained fluid to close the circuit through the rod and main body of fluid to the other electrode and upon withdrawal of the field of the external magnet to allow the cup to depart from the spaced apart electrode to open the circuit through the switch. 100

CERTIFICATE OF CORRECTION.

Patent No. 1,915,683.

June 27, 1933.

IRA E. McCABE.

It is hereby certified that error appears in the printed specification of the above numbered patent requiring correction as follows: Page 2, line 77, claim 2, strike out the word "fluid" and insert the same after "conducting" in line 76; and that the said Letters Patent should be read with this correction therein that the same may conform to the record of the case in the Patent Office.

Signed and sealed this 22nd day of August, A. D. 1933.

M. J. Moore.

Acting Commissioner of Patents.
